(57) **CLAIM**

The ornamental design for a medical imaging apparatus, as shown and described.

DESCRIPTION

FIG. 1 is a front view of a medical imaging apparatus showing our new design;

FIG. 2 is a back elevational view thereof;

FIG. 3 is a top plan view thereof;

FIG. 4 is a bottom plan view thereof;

FIG. 5 is a right-side elevational view thereof;

FIG. 6 is a left-side elevational view thereof; and,

FIG. 7 is a perspective view taken generally from the top, front, left-hand side thereof.

The broken lines shown in the drawings represent portions of the medical imaging apparatus that form no part of the claimed design.
